US0D1087396S

(12) **United States Design Patent** (10) **Patent No.:** **US D1,087,396 S**
(45) **Date of Patent:** **** Aug. 5, 2025**

(54) **CURVED FOUNDATION SUPPORT**

(71) Applicant: **Blake Joseph Heron**, Virginia Beach, VA (US)

(72) Inventor: **Blake Joseph Heron**, Virginia Beach, VA (US)

(**) Term: **15 Years**

(21) Appl. No.: **29/848,700**

(22) Filed: **Aug. 4, 2022**

(51) **LOC (15) Cl.** **25-99**

(52) **U.S. Cl.**

USPC **D25/199**; D8/376

(58) **Field of Classification Search**

(57) **CLAIM**

The ornamental design for a curved foundation support, as shown and described.

DESCRIPTION

FIG. 1 is a perspective view of the front of the invention; FIG. 2 is a perspective view of the rear thereof; FIG. 3 is a top plan view thereof; FIG. 4 is a front elevation view thereof; and, FIG. 5 is a side elevation view thereof.

The right side elevation view is identical to the left side elevation view, and the front elevation view is identical to the rear elevation view.

Dashed lines are used to show the environment and other shading lines are used, neither of which comprise any of the claimed invention.

1 Claim, 5 Drawing Sheets
